ARC LAMP CONTROL

Ben Hopkins, Indianapolis, and Ralph A. Woods,
Morgantown, Ind.

Application November 18, 1946, Serial No. 710,426

5 Claims. (Cl. 314—53)

1

This application relates to electric arc lamps, especially to electrode feeding mechanism for such lamps.

Lamps of the type to which this invention relates are commonly used for motion picture projection. In them, positive and negative carbon electrodes are fed toward each other, usually from opposite directions along the axis of an elliptical reflector, to provide a continuous arc at or about the focal point of the reflector. To maintain the continuous arc of the desired characteristics at the desired point, the two electrodes must be fed accurately toward the arc at different rates proportional to their different rates of consumption. Commonly, the negative carbon is supported, and fed, through an opening in the center of the reflector; and the positive carbon is fed by an arm through a guide, both of which necessarily lie in the path of light.

The electrodes are of carbon, often sheathed with a thin layer of conductive metal. They are relatively fragile, yet they must be mechanically supported and connected to an electrical circuit in such a positive way that there is no arcing or excessive voltage drop at the connections. They must be frequently replaced and more frequently must be advanced in their holders if they are to be fully consumed. On each such occasion the holders must be reset with respect to the driving mechanism.

In prior lamps, the electrode holders impose considerable danger to the fragile carbon electrodes, both of cracking the electrode itself and of breaking the metallic sheath of the electrode. In addition, the operating mechanism for the holders has been so arranged with respect to the arc that it was heated excessively and was difficult and hazardous to use, as for resetting electrodes, without excessive delay to permit the whole lamp to cool.

Prior electrode holders have been driven at fixed relative rates, as by a pair of screws geared to give feeding rates generally proportional to the consumption of the two electrodes. Such prior drives are designed to use particular and uniform sets of electrodes, under particular and rigid conditions of current supply. Such drives are inflexible, and usually require constant attention and adjustment by an operator, to compensate for variations in current supply and especially for the particular characteristics of the current supply which is available in a particular installation. Without such constant attention and frequent manual adjustment, the variations from the conditions for which the lamp was

2

specifically designed cause the arc to travel from its desired point either toward or away from the reflector, with consequent loss in the quality of light produced.

- 5 It is the object of our invention to provide improved electrode supply mechanism for an arc lamp, which will provide a good electrical connection between the electrodes and their holders with substantially no danger of breaking or cracking the electrodes, which will be adapted for ready and quick interchange and resetting of the electrodes by means that is removed from the heat of the lamp, which imposes a minimum of obstruction in the light path, which will give improved electrode feeding at proper relative speeds to maintain the arc with the proper characteristics and in the proper position, which may be readily adjustable over a range to suit the particular characteristics of current available in 10 particular installations and when so adjusted will truly maintain a proper arc at the desired point without constant or frequent attention, and which will lend itself to ready conversion for operation of the lamp at different intensities.
- 15 25 In a preferred form of our invention, we drive electrode carriages along parallel feed screws, continuously drive one of said screws by means responsive to the current across the arc, and drive the second from that same source through an 20 infinitely-variable, constant drive. On each electrode carriage we mount an electrode holder which provides for positive feed of its electrode toward the arc.

- 30 The negative electrode holder rises from its carriage behind the reflector and feeds its electrode through a center opening in the reflector. The holder provides some universal movement for the electrode, and the forward end of the electrode is positioned by an adjustable guide which also extends through the reflector opening. 35 The positive electrode holder passes through a laterally open slot in the floor of the lamp, then rises outside the light beam to the level of the reflector axis. A radial arm extends inward at 40 that level to hold the positive electrode on the reflector axis. The arc-end of the positive electrode is guided at the end of an opposite radial arm extending horizontally inward from the opposite side of the reflector from the holder arm. 45 The holder and guide arms are symmetrically arranged at about the level of the arc and are relatively thin; and they cause minimum disturbance to the light beam and absorb a minimum amount of heat.
- 50 55 Each electrode is firmly gripped between mem-

bers formed to engage its surface over substantial curved areas of its circumference and over a considerable axial distance, for example 2 to 4 times the diameter of the electrode, which gives an extensive area of engagement between each electrode and its holder. The electrode gripping parts are at the ends of arms extending inwardly and are mechanically connected to be thrust toward each other by manual operation, to grip the electrodes with considerable pressure. The arrangement, involving a large gripping area on parts thrust toward each other, gives improved electric contact, permits the use of considerable pressure to enhance the electrical connection substantially without danger of damage to the electrodes, and holds the electrodes firmly throughout their operation. The gripping parts are operated manually by handles positioned at the remote ends of the supporting arms and outside the light beam, the negative electrode handle being behind the reflector, and the positive electrode handle being at the outer end of the radial holder arm; and we have found that our arrangement permits the electrode to be reset and replaced quickly and readily without unnecessary delays for cooling and without danger of breakage.

The accompanying drawings illustrate my invention. In such drawings, Fig. 1 is a plan showing pertinent parts of an arc lamp embodying my invention; Fig. 2 is a side elevation of the structure shown in Fig. 1; Fig. 3 is an end elevation of structure shown in Fig. 1, with the base in section; Fig. 4 is a vertical longitudinal section of the negative electrode-holder; Fig. 5 is a horizontal section in the plane of the axis of the two electrode-driving screws; Figs. 6 and 7 respectively are end and top elevations of the driving connections between the two electrode-driving screws; and Fig. 8 is an enlarged plan of the gripping head of the positive-electrode holder.

The arc lamp structure shown in the drawing includes a base 10 which supports the housing and other usual parts of the lamp. It is desirably of inverted box form and houses the electrode driving mechanism below its top wall 15. A reflector 11 is mounted on the base 10 by usual means to provide adjustment for aligning its axis as desired. A negative electrode 12 extends through a central opening in the reflector, and a positive electrode 13 is positioned in alignment therewith to arc at the point 14 between the ends of the electrodes 12 and 13.

The electrode feeding mechanism includes a pair of shafts 18 and 19 journaled in the end walls of the base 10 and extending longitudinally thereof, parallel to the axis of the reflector 11. The shaft 18 is positioned below the axis of the reflector 11 and desirably slightly to one side thereof. It is threaded over approximately the rear two fifths of its length, and is used to drive the negative carbon 12. The shaft 19 is parallel to the shaft 18, conveniently in the same horizontal plane, and spaced outwardly from the shaft 18. It is threaded over approximately the front three fifths of its length, and is used to drive the positive carbon 13. The shafts 18 and 19 are drivingly interconnected by means which will be described, to rotate at speeds to give the desired proportional feeding rates of the two electrodes.

A carriage 20 for the negative electrode is slidably mounted on the two shafts 18 and 19 at the threaded end of the shaft 18. It carries a worm gear 21 on a horizontal axis below the shafts 18 and 19, in engagement with the threads of the

shaft 18. The shaft 23 of the gear 21 extends outward through a slot in the side wall 16 of the base 10, and carries an insulated handle 22 at its end. A friction brake 24 normally holds the shaft 23 against rotation with respect to the carriage 20, so that rotation of the shaft 18 causes longitudinal travel of the carriage 20. Manual operation of the handle 22 rotates the worm 21 against the friction brake, to adjust the carriage along the threads of the driving shaft 18. From the carriage 20 a post 25 rises through a slot 26 in the top wall 15 of the base, to support the negative electrode holder. The holder comprises an inverted L-shaped member 27, the vertical leg of which is loosely bolted against the side of the post 25, as by a pair of bolts 28 loosely received in holes 29 through the vertical leg of the member 27. The horizontal leg 30 of the member 27 is offset so that it overlies the end of the post 25. It extends forwardly, and at its forward end carries a depending boss 31. The horizontal leg 30 is drilled to provide a longitudinal, inclined bore to receive a clamping slide 32, the rear end of which carries a rack 33 in engagement with a gear 34 manually operable by a handle 35. A hole longitudinally through the boss 31 forms a seat to engage the lower circumferential half of the negative carbon electrode 12; and the forward end of the slide 32 is shaped to engage the upper half of the electrode 12. The engaging surfaces, especially on the boss 31, are desirably curved to mate with the surface of the electrode, and extend axially of the electrode 12 a considerable distance, for example 2 to 4 times the diameter of the electrode. The electrode 12 is clamped in place by operation of the handle 35 to cause the gear 34 to move the gripping slide 32 forwardly to wedge itself into gripping engagement with the electrode 12.

From the holder 30-35, the negative electrode extends forward through an opening in the center of the reflector 11, to the arcing point 14. Just short of its end at the arcing point 14 the electrode 12 rests in a notch 38 of an adjustable guide 39 which extends forwardly from a point of support through the central opening of the reflector 11. The holder 30-35 supports the electrode 12 substantially on the axis of the reflector 11, and the looseness of the connection between the vertical leg 27 of the electrode holder of the post 25 permits the electrode 12 to adjust itself to the position of the guide 39.

A carriage 40 for the positive electrode 13 is slidably received on the forward ends of the shafts 18 and 19. It is interconnected to the threads on the shaft 19 by a worm gear 41 on a shaft 42. Such shaft 42 extends horizontally below the shafts 18 and 19 and through a slot in the side wall 16 of the base, where it carries an operating handle 43. A friction brake 44 normally locks the gear 41 against rotation with respect to the carriage 40 so that rotation of the shaft 19 causes longitudinal travel of that carriage 40. As is best seen in Fig. 3, a post 45 for supporting the positive electrode rises from the carriage 40 first vertically, then horizontally inward beneath a shielding cover 17 forming part of the top wall 15 of the base 10, then outward and upward in a curve outside the path of light from the reflector. From the upper end of the post 45, an arm 46 extends inward to support the positive electrode 13 on the axis of the reflector. Such arm 46 is inclined to the axis of the reflector 11, as may be seen in Fig. 1, so that it supports the electrode 13 at a point near its rear

end; which permits a greater length of the electrode to be fed without resetting the holder. The arm is in the form of a relatively flat bar, bent laterally at its end to extend at a right angle to the axis of the reflector. It is positioned with a thin edge toward the reflector, so that it presents a minimum obstruction in the light beam.

At its inner end, the arm 46 carries a stop 48, and at its outer end a lug 49. A thrust member 51, desirably formed of sheet metal bent to loosely embrace the arm 46, is slidably mounted on the arm between the lug 49 and the stop 48. The depending wall on the reflector side of said member 51 terminates in an angular portion 53 which is normal to the reflector axis and rides against the side of the parallel end of the arm 46, to cause the forward end of the member 51 to move at right angles to the reflector axis as it approaches gripping engagement with its electrode. The inner end of the member 51 carries a pressure member 52 to move toward the stop 48. A thrust screw 50 is threaded through the lug 49 and operatively connected to the thrust member 51, and is operated by a handle 47 positioned beyond the outer end of the arm 46. Desirably, the meeting faces of the members 48 and 52 are respectively shaped to present seating areas which fit the cylindrical surface of the positive electrode 13 over both a considerable axial extent and a considerable circumferential extent.

From the holder, the positive electrode extends toward the arcing point 14, in alignment with the negative electrode 12. Just short of the end of the positive electrode 13, it is guided by engagement with a guide surface on a radial guide arm 55, supported from the opposite side of the lamp from the holder arm 46. Such guide arm 55 is supported on a post 56 which is mounted on the base 10 and which extends upward and outward therefrom outside the path of light. The guide arm 55 is relatively thin where it cuts the path of light so that like the arm 46 it presents a minimum obstruction in the path of light. The two arms are generally symmetrical and are positioned and shaped to cause a minimum disturbance in the light beam.

This arrangement permits operation of the positive electrode holder from a relatively cool point, so that it is readily possible to reset or replace the positive electrode in the holder 46-52 without waiting for the lamp to cool; for the only part which needs to be touched is the operating handle 47 for the pressure screw 50 of that holder, and this handle 47 remains sufficiently cool during operation of the lamp so that no unnecessary wait is required when the arc is extinguished before that handle 47 may be operated manually to replace a positive electrode 13.

The electrode feed screws 18 and 19 are driven by a motor 60. This operates a gear 61 which meshes with a gear 62 mounted on the end of the screw 18. The screw 19 is constantly operated from the same source, conveniently from the gear 62, by an infinitely-variable positive driving train. As shown, this driving train includes an idler gear 63 carried by an arm 64 pivotally mounted on the shaft 18. The side faces of the idler gear 63 are beveled, and engage between opposed faces 65 of a pair of cones 66 and 67 on the shaft 19. The cone 67 is adjustable toward and from the cone 66 to vary the depth of engagement between the idler gear 63 and the conical faces 65, and thus to vary the driving ratio between the shafts 18 and 19. The axis of the idler gear 63 is parallel to the shafts 18 and 19, and is spaced from the plane of the axes of those

shafts by a distance which depends upon the adjustment of the cone 67 and the depth of engagement between the idler 63 and the cones 66 and 67. The idler 63 enters between the cones 66 and 67 in the direction of rotation of the gear 62 and at an angle with a line joining the centers of the shafts 18 and 19, so that driving operation of the train tends to force the idler 63 into firm engagement with the faces 65 of the cones 66 and 67. The weight of the arm 64 and of the idler 63 also tends to move the idler 63 into engagement with the faces 65, and a spring, shown as a tension spring 68, may be used to urge the arm 64 in that same direction. Thus, as shown in Fig. 6, where the shafts 18 and 19 both rotate in a clockwise direction, the idler 63 is above and between the gear 62 and the cones 66-67, and is urged into engagement with the cones by both the weight of the arm 64 and gear 63 and the tension of the spring 68, and by the action of the parts during driving operation.

The motor 60 is electrically connected in known manner so that its operation is responsive to the length of arc gap between the electrodes, and maintains such gap at the proper length. Upon installation of the machine, the cone 67 is adjusted to give a speed ratio between the shafts 18 and 19 so that they feed their respectively associated electrodes at the proper relative rates to cause the arc to remain at the desired point. This adjustment must be by trial, to suit the particular characteristics of the current supplied. Usually, the current supply is adjustable—as by changing taps on a rectifier—to give approximately the characteristics for which the lamp is designed, but it is usually difficult and frequently impossible to obtain exactly the desired current characteristics by adjustment of the current supply. Although the lamp will operate even though the current varies quite widely from that for which the lamp is designed, the arc will not remain in the proper position, but will "walk" or travel along the axis of the reflector, by consuming one or the other of the electrodes at too great a relative rate. This walking is readily overcome by adjustment of the speed ratio between the shafts 18 and 19. If the arc travels toward the reflector, the relative speed of the positive electrode is reduced, by adjusting the cone 67 toward the cone 66 to decrease the depth of engagement between the idler 63 and the faces 65. Conversely, if the arc travels away from the reflector, the feeding rate of the positive electrode is increased, by adjusting the cone 67 away from the cone 66 to increase the depth of engagement between the idler 63 and the faces 65.

Our electrode feeding mechanism provides feeding rates for the two electrodes which are truly proportional to their respective rates of consumption under all normal conditions in any usual installation, and the arc will normally remain fixed in any desired point without attention or manual correction by the operator. The lamp may be readily adjusted for operation at higher intensity at higher amperage with larger electrodes, merely by readjusting the variable drive to the proportional rates of feed required for the new conditions.

In preparing the lamp for operation, the carriages 21 and 40 are retracted along their feed screws 18 and 19 by rotation of the handles 22 and 43, and electrodes 12 and 13 are inserted in their respective holders. The electrode 12 is inserted by operating the handle 35 to retract the clamping member 32, an electrode 12 being then readily inserted from the rear through the hole

in the boss 31, and the handle 35 is then turned to force the clamping member 32 forward to firmly clamp the electrode 12 and establish a firm mechanical and electrical connection between it and its holder. The electrode 13 is inserted by operating the handle 47 to retract the thrust member 51 and open the clamping members 48 and 52 of the positive-electrode holder. The electrode is then placed between the clamping members, and the thrust member 51 moved forward by the handle 47 to firmly grip the positive electrode 13.

Both electrodes are gripped over a large area by fitting surfaces, which permits the electrodes to be firmly gripped under considerable pressure, to give a good mechanical and electrical connection between them and their holders, without danger of breaking or cracking the electrodes. We have found that there is no danger of such breakage within the limits of manual tightening of the gripping members 35 and 47, and that such manual tightening readily gives proper and ample mechanical and electrical connection for the electrodes.

We claim as our invention:

1. In an arc lamp, a pair of feed screws respectively connected to feed the negative and positive electrodes, an electric motor positively connected to drive one of said feed screws, an infinitely-variable constant driving train interconnecting the driven feed screw with the other feed screw.

2. In combination in an arc lamp, a pair of feed screws respectively connected to feed the positive and negative electrodes, an electric driving motor geared to one of said feed screws, a pair of cones mounted on the other feed screw and provided with opposed conical faces, an idler gear driven by the gear train to said driven feed screw, said idler gear being beveled at the edges of its side faces and being positioned with said beveled surfaces in engagement between the conical faces of said cones, said idler gear entering between said cones in the direction of rotation of its driving gear, and means urging said idler gear into engagement with said cones, said cones being adjustable to vary the spacing between them whereby to vary the speed ratio between the two feed screws.

3. In an arc lamp, negative-electrode feeding mechanism, independent positive-electrode feeding mechanism, means for positively driving one

of said feeding mechanisms, and an infinitely variable constant driving train interconnecting said other feeding mechanisms to said driving means.

4. In combination in an arc lamp, a base, a reflector mounted on said base, a negative-electrode feed screw in said base parallel to the axis of said reflector and below its axis, a positive-electrode feed screw parallel to said first feed screw and spaced laterally therefrom toward one side of the base, a motor mounted on said base on the opposite side thereof from said positive-electrode feed screw, a gear on said negative-electrode feed screw driven by said motor, a pair of cones on said positive-electrode feed screw aligned with said gear, said cones being formed to present opposed conical faces, an idler gear driven from said first gear and having beveled edges in driving engagement with the conical faces of said cones, said cones being adjustable to vary the spacing between them whereby to vary the speed ratio between said two feed screws.

5. In an arc lamp, a pair of feed screws respectively connected to feed the negative and positive electrodes, means for continuously driving one of said feed screws, and an infinitely variable constant driving train to the other of said feed screws, comprising a rotor having beveled edges, and a pair of coaxial cones relatively adjustable axially and with conical faces in driving engagement with the beveled edges of the rotor, the rotor and cones being movable toward each other whereby axial adjustment of the cones varies the depth of engagement between the cones and rotor to vary the ratio of said train and adjust the relative speeds of said two feed screws.
